Atty's.

UNITED STATES PATENT OFFICE.

IMMANUEL PFEIFFER, OF BEDFORD, MASSACHUSETTS, ASSIGNOR, BY DIRECT AND MESNE ASSIGNMENTS, TO BLUE TIP PILE WIRE & KNIFE COMPANY, OF BEDFORD, MASSACHUSETTS, A CORPORATION OF MASSACHUSETTS.

PILE-WIRE KNIFE.

Application filed April 14, 1925. Serial No. 23,063.

This invention relates to a pile-wire knife having novel means providing for removal of the blade from, and its replacement in, the blade-holder.

The invention will be best understood by reference to the following description, when taken in connection with the accompanying drawings of one specific embodiment thereof, while its scope will be more particularly pointed out in the appended claims.

In the drawings:—

Fig. 1 is an elevation of a pile-wire knife exemplifying the invention;

Fig. 2 is an elevation of the same, as viewed from the opposite side thereof;

Fig. 3 is an elevation, partly in section, illustrating the mode of attaching and detaching the blade;

Fig. 4 is a sectional view, on line 4—4 of Fig. 1;

Fig. 5 is a sectional view, on line 5—5 of Fig. 1; and

Fig. 6 is a sectional view, on an enlarged scale, on line 6—6 of Fig. 3.

Referring to the drawings, and to the embodiment of the invention which is selected for exemplification, there is shown a pile-wire knife, comprising a blade 7 and a blade-holder 8. Herein, the blade has a tapered formation, it having a narrow rear end 9 and a wide forward end 10. The term "forward" as herein employed in connection with the blade and its holder is intended to refer to the free end which advances across the fabric on its forward stroke. On the other hand the term "narrow" as applied to the blade is intended to refer to that end of the blade which is at the rear during the forward stroke of the free end of the knife across the fabric. The blade is provided with a cutting edge 11, which, during the rearward stroke of the wire, cuts the loops of the fabric.

The blade-holder herein is conveniently formed of sheet metal folded upon itself to provide two walls 12 and 13, between which is a groove 14 to receive the blade. Herein, the wall 13 extends longitudinally beyond the wall 12 and presents a head 15, which is wider than the wall 12 and wider than the shank of the holder, and this head has a suitably shaped tip or point 16, as is usual with pile wires. The rear end of the blade, herein, is narrower than the shank of the

holder, and is completely concealed by the 55 walls which present the groove for the reception of the blade.

The rear end of the blade is retained in the groove by an abutment 17, which overhangs a portion of the blade in such a manner that removal of the latter from its normal position represented in Figs. 1 and 2 can be accomplished only by swinging the blade on the abutment, as a fulcrum (see Fig. 3). Inasmuch as the

fulcrum is at the rear end of the blade, this 60 construction may be employed in connection with narrower wires, because even with the narrowest wires, the head at the forward end

can be made sufficiently wide to carry means to retain the forward end of the blade in the 65 groove, in the manner presently to be described.

In the present example, the abutment 17 is conveniently presented by a strip of metal, which is inserted in the groove 14, and is secured in place by forming one or 70

more indentations 18 (one of which is shown in section in Fig. 6) in one of the side walls 75

of the holder, thereby squeezing such wall into the strip which is interposed between the walls, and thus securely holding the same 80

in place.

The forward end of the blade is retained in the groove by the cooperative action of a protubérance 19, presented by the wall 15

and a wall 20, which, in the present example, 85

is conveniently formed as a tongue struck up from the wall 15. The walls 15 and 20

embrace the blade, as best shown in Fig. 4, while the protuberance 19 presents an ob- 90

struction to withdrawal of the blade from the groove by swinging movement on its 95

fulcrum 17. The wall 20 is resiliently re- 100

lated to the wall 15, it being in the form of a spring tongue (see Fig. 5), which is adapt- 105

ed to recede from the wall 15 when sufficient pressure is exerted against the blade in its

own plane toward the protuberance 19, the latter being rounded or beveled, to permit the blade to ride over it.

When the blade is in place, this tongue resists lateral move- 110

ment of the blade, and accurately positions the latter with reference to the opposite wall, irrespective of the width of the groove with

reference to the thickness of the blade. This results in accurate cutting of the loops, and 115

in uniform appearance of the work. When the blade is in place, the tongue 20 constitutes an abutment, which defines the posi-

tion of the blade lengthwise in one direction, while the abutment 17 defines its position lengthwise in the opposite direction.

The shank of the pile-wire knife in practice is attached to the end of the pile wire, and is operated in a manner too well known to those skilled in the art to require description. When the blade becomes dulled, it may be removed and replaced by a sharp one, with the greatest facility, and when in place, is securely locked against accidental disengagement from its holder.

Having thus described one embodiment of the invention, but without limiting myself thereto, what I claim and desire by Letters Patent to secure is:—

1. A pile-wire knife comprising, in combination, a blade, and a blade-holder having two walls presenting a groove which receives a longitudinal edge of said blade, blade-retaining means presenting a fulcrum on which the rear end of said blade swings in attaching it to and detaching it from said holder, means to resist forward movement of said blade with relation to said holder, and blade-retaining means comprising a protuberance presented by one of said walls and affording an obstruction forward of said fulcrum and without the perimeter of said blade to resist removal of the latter.

2. A pile-wire knife comprising, in combination, a blade and a blade-holder having two walls presenting a groove which receives a longitudinal edge of said blade, blade-retaining means presenting a fulcrum on which the rear end of said blade swings in attaching it to and detaching it from said holder, means to resist forward movement of said blade with relation to said holder, and blade-retaining means comprising a beveled protuberance presented by one of said walls and disposed without the perimeter of said blade in position to be engaged by another longitudinal edge of said blade.

3. A pile-wire knife comprising, in combination, a blade, and a blade-holder having two walls presenting a groove which receives a longitudinal edge of said blade, blade-retaining means presenting a fulcrum on which one end of said blade swings in attaching it to and detaching it from said holder, and blade-retaining means comprising an obstruction in the path of another longitudinal edge of said blade, and yielding means normally to retain said blade in the plane of said obstruction, and adapted to yield to permit said blade to become displaced from said plane and to pass over said obstruction.

4. A pile-wire knife comprising, in combination, a blade having a narrow end and a wide end, and a blade-holder presenting a groove which receives one edge of said blade, an abutment which overhangs said narrow end and retains the latter in said groove, and

two walls which embrace said wide end, one of said walls being resiliently related to the other and the latter presenting a protuberance which normally retains said wide end in said groove by engagement with a longitudinal edge of said blade. 70

5. A pile-wire knife, comprising, in combination, a blade, and a blade-holder presenting a groove which receives one edge of said blade, an abutment which overhangs one portion of said blade and retains such portion in said groove, and two walls which embrace another portion of said blade, one of said walls being resiliently related to the other and the latter presenting a protuberance which normally retains such other portion of said blade in said groove by engagement with a longitudinal edge of said blade. 75

6. A pile-wire knife comprising, in combination, a blade, and a blade-holder having a shank presenting a groove which receives one edge of said blade, an abutment within said groove, which overhangs one portion of said blade and retains such portion in said groove, and a head presenting two walls which embrace another portion of said blade, one of said walls being resiliently related to the other and the latter presenting a beveled protuberance which normally retains such portion of said blade in said groove by engagement with a longitudinal edge of said blade. 80

7. A pile-wire knife comprising, in combination, a blade, and a blade-holder having two walls presenting a groove which receives said blade, means to retain one end of said blade in said groove, and means to retain the other end of said blade in said groove, the last-mentioned means including a yielding tongue and a beveled protuberance presented by one of said walls. 90

8. A pile-wire knife comprising, in combination, a blade, a blade-holder having two walls which embrace said blade, and blade-retaining means including a beveled protuberance presented by one of said walls and presenting an obstruction to removal of said blade, and a laterally resilient tongue which yieldingly resists movement of said blade from such wall. 100

9. A pile-wire knife comprising, in combination, a blade, a blade-holder having two walls which embrace said blade, one of said walls extending both laterally and longitudinally beyond the other and presenting a protuberance which resists outward movement of said blade from said groove, and a laterally resilient tongue which yieldingly resists movement of said blade from such extended wall. 110

10. A pile-wire knife comprising, in combination, a blade, and a blade-holder having two walls presenting a groove which receives a longitudinal edge of said blade, blade-retaining means comprising a fulcrum, 120

on which the rear end of said blade swings in attaching it to and detaching it from said holder, and laterally-resilient means presenting at the forward end of the blade an abutment which receives the longitudinal thrust of said blade in a forward direction and which yieldingly resists lateral movement of said blade.

11. A pile wire knife comprising, in combination, a blade, and a blade-holder having two walls presenting a groove which receives a longitudinal edge of said blade, blade-retaining means comprising a fulcrum on which the rear end of said blade swings in attaching it to and detaching it from said holder, and a laterally resilient tongue which engages one face of said blade, said tongue presenting an obstruction which receives the forward thrust of said blade.
12. A pile wire knife comprising, in combination, a blade, and a blade holder having two walls presenting a groove which receives a longitudinal edge of said blade, and means presenting a fulcrum on which the rear end of said blade swings in attaching it to and detaching it from said holder, one of said walls being extended beyond the other both laterally and longitudinally in a forward direction, said extended portion presenting two protuberances one of which is adapted to be engaged by the forward end of said blade to limit forward displacement

of said blade and the other of which is adapted to be engaged by the other longitudinal edge of said blade to limit swinging 35 movement of said blade in an outward direction from said groove, the last-mentioned protuberance being bevelled to permit said blade to ride up and over the same during removal of said blade. 40

13. A pile wire knife comprising, in combination, a blade, and a blade holder having two walls presenting a groove which receives a longitudinal edge of said blade, one of said walls extending longitudinally in a forward direction beyond the other and having a portion which is wider than the other, and means presenting a fulcrum on which the rear end of said blade swings in attaching it to and detaching it from said holder, said longitudinally extending wall presenting a protuberance at the front end of said blade to resist forward movement of said blade in said holder, and said wider portion presenting beyond the limits of the 50 other wall a rounded protuberance which is adapted to be engaged by another longitudinal edge of said blade to resist removal of the latter by swinging movement in an outward direction on said fulcrum. 60

In testimony whereof, I have signed my name to this specification.

IMMANUEL PFEIFFER.
